UNITED STATES PATENT OFFICE.

FELIX F. ISBANER AND PHILIP A. DASH, OF CHICAGO, ILLINOIS.

WINDOW CONSTRUCTION.

Application filed December 15, 1926. Serial No. 154,877.

This invention relates to a window construction and has special reference to a window construction wherein a sash is pivotally and slidably mounted in a frame.

5 More particularly this invention relates to a window construction in which the sash is pivotally and slidably mounted in the frame in such manner that the sash is sealed when the window is closed or in a vertical position and unsealed when it is desirous of operating said sash on its pivotal construction.

In the present window construction, many hazards are encountered in the cleaning and repairing of windows, and this is especially true in all buildings of several stories where the workman must sit on the outer window ledge while working. In the use of our novel window construction, the workman may stand on the floor and face the window from the inside of the room or other enclosure and when necessary operate the window or sash on its pivotal construction and bring the outside of the window into a reverse position, that is, the outer side of the window can become the inner side, whereby, of course, it is readily accessible for the required cleaning or repair. Further, the upper window sash may be drawn down and pivoted to a position which is within the easy reach of the workman thereby obviating the use of ladders and other articles otherwise necessary for work on the upper sash.

One of the objects of this invention is to 35 provide a window construction wherein a sash is pivotally and slidably mounted within a frame-work.

A further object of this invention is to provide a window construction having 40 means whereby the sash is sealed within a frame, said sash being pivotally and slidably mounted in said frame and the sealing means being operable into and out of engagement with said sash.

45 Further objects of this invention will be apparent from the description and accompanying drawings forming a part of this specification to which reference may now be had for a more complete understanding of 50 the characteristic features of this invention, and in which drawings:

Figure 1 is a perspective view of a portion of the window construction embodying this invention;

55 Fig. 2 is a side elevational view of the

window construction showing the frame thereof in section;

Fig. 3 is a sectional view on the line 3—3 of Fig. 2;

Fig. 4 is a sectional view taken on the line 60 4—4 of Fig. 3;

Fig. 5 is a view similar to Fig. 4 but showing a changed position of one of the operable parts thereof; and

Fig. 6 is a side elevational view partly in 65 section showing in detail the pivotal construction.

Referring now particularly to the drawings, a pair of sashes 10 and 11 are shown mounted in a frame 12, these sashes comprising the usual form of sash construction. Said sashes 10 and 11 are mounted in different planes in the frame 12, as is the usual method of construction, known as the check rail window, whereby the sash 10 may be 70 lowered and the frame 11 may be raised independently of each other. The frame 12 is provided with a pair of grooves 13 and 14 on each vertical side, and are adapted 75 to receive plates 15 which are in slidable engagement therewith. The plates 15 in turn have plates 16 suitably fixed thereon, as by means of screws 17, said plates 16 extending outwardly beyond the outer edges of said frame. A bearing member 18 projects from said plates 16, and is preferably disposed centrally thereof and integrally 80 therewith.

The slidable plate 15, upon which the bearing member 18 is carried, is fixed to one 90 end of a rope or other suitable means, while the other end of said rope having the usual weighted members (not shown) is attached thereto.

The sashes 10 and 11 are provided with 95 apertures into which are positioned sleeves 20 for engaging the bearing member 18. These sleeves 20, which are preferably of metal, are disposed centrally of said edges, although it is to be understood that this 100 positioning may be varied at will, and the sleeves disposed adjacent either end of the sash, or otherwise.

In the operation of the device thus far described, the sashes may be raised or lowered in the frame and be guided in their movement by means of the engaging plates 15 sliding in the grooves 14. In any of the positions into which these sashes may be moved, said sashes may be revolved on their 110

pivots so that either side of the sash or window may be exposed to the inside of the enclosure in which the frame 12 is positioned. Since the plate 16 projects from the edge 5 of the frame 12, and as the vertical edge of the sash has engagement with the vertical edge of the frame, it is desirable to provide a recess 21 in said sash for receiving the plate 16, said recess to be of a size that 10 will permit the sash to revolve about the fixed plate 16.

In order that the sashes may be in a substantially sealed relation with the frame when in a closed position, the frame is 15 provided with slots 22 adjacent the outer and inner edges of the sash members. Elongated strips 23 of any suitable material are disposed within these slots 22 and have slideable engagement therewith. The slots 22 20 are of sufficient depth to permit the strips 22 to be received therein with no portion of the strips 23 projecting beyond the outer edge of the frame.

By being slideable in the slots 22, the 25 strips 23 may be moved outwardly from the slots and extend over the outer and inner edges of the sash members, thereby effecting a sealed relation between the sash members and the frame.

30 In order to manually operate these strip members into and out of engagement with the sash members, a crank arm 24 is mounted within a frame in any suitable manner, as for instance, being journaled in the bearing members 25, the arms of said crank members engaging slotted portions 26 in projections 27 formed preferably integrally with the strips 23. These projecting portions 27 are provided with suitable openings 40 28 into which they are received when the strips are drawn back out of engagement with the sash members. The crank members are preferably disposed adjacent the upper and lower ends of said frame, as 45 shown in Fig. 2 of the drawings.

In the operation of these strips, the crank members are rotated from the inside of the enclosure, whereby the arms of said crank members operate in the slots 26 to push the strips outwardly into an engagement with the outer and inner ends of the sash members, and operate by a reverse rotation of the crank members to draw the strips out of engagement with the inner and outer ends 50 55 of the sash members, as clearly shown in Figs. 4 and 5 of the drawings. This construction seems to be the most simple, al-

though it will be apparent that various means for actuating these strip members may be utilized, this construction being shown 60 for purposes of illustration to indicate the operable arrangement of the members.

While we have described but a single embodiment of this invention, it is to be understood that various modifications thereof will 65 be apparent to those skilled in the art without departing from the spirit and scope of this invention, and therefore, it is desired that the same be limited only by the scope of the appended claims and the prior art. 70

We claim:

1. A window construction comprising a frame having grooves on each vertical side thereof, a plate for engagement with each of said grooves and not extending beyond the outer edges of said frame, a plate having a bearing member extending therefrom and secured to said first mentioned plates, a sash pivotally mounted on said bearing members and disposed in said frame whereby a snug engagement exists between the edges of said frame and said sash in a normally closed position, said frame having slots adjacent the outer and inner edges of said sash, and elongated strips for slideable engagement horizontally of said slots and extending over said outer and inner edges of said sash in one position thereof to substantially seal said sash and said frame. 80

2. A window construction comprising a frame having grooves on each vertical side thereof, a plate for engagement with each of said grooves and not extending beyond the outer edges of said frame, a plate having a bearing member extending therefrom and secured to said first mentioned plate, a sash pivotally mounted on said bearing members and having a cut-away portion into which said second mentioned plate is received whereby a snug engagement exists 90 between the edges of said frame and said sash in a normally closed position, said frame having slots adjacent the outer and inner edges of said sash, elongated strips for slideable engagement with said slots, and a crank arm supported in said frame and for engagement with said projections whereby said strips are moved into and out of engagement with the edges of said sash. 100

In witness whereof we have hereunto subscribed our names.

FELIX F. ISBANER.
PHILIP A. DASH.
